UNITED STATES PATENT OFFICE.

HERBERT P. SEYMOUR, OF HARTFORD, CONNECTICUT, ASSIGNOR OF TWO-THIRDS TO HARRY PRICE AND CHARLES W. DOUGHERTY, OF SAME PLACE.

MEANS FOR SECURING SCREW-HOOKS, &c., IN CEILINGS OR OTHER HIGH STRUCTURES.

SPECIFICATION forming part of Letters Patent No. 562,041, dated June 16, 1896.

Application filed January 21, 1896. Serial No. 576,272. (No model.)

To all whom it may concern:

Be it known that I, HERBERT P. SEYMOUR, a citizen of the United States, residing at Hartford, in the county of Hartford and State of Connecticut, have invented certain new and useful Improvements in Means for Securing Screw-Hooks, Screw-Eyes, or Similar Fixtures in Ceilings or other High Structures, of which the following is a specification.

10 This invention relates to means for securing screw-hooks, screw-eyes, or similar fixtures in a ceiling or other high structure, and it is more particularly designated as a "screw-hook-driving" device.

15 The object of the invention is to provide a device of this character which is simple in construction and by means of which a screw-hook, screw-eye, or analogous fixture can be quickly and easily secured in position in the 20 ceiling of a room or other high structure without the use of a ladder or similar device.

In the drawings accompanying and forming part of this specification, Figure 1 is a side view of the screw-hook-driving device, the 25 pole or handle thereof being broken off. Fig. 2 is a side view of the same, taken at right angles to the view shown in Fig. 1 and having a part broken away and a part thereof in section. Fig. 3 is a vertical sectional view 30 taken in line *a a*, Fig. 5, parts thereof being in full lines. Fig. 4 is a partly vertical sectional view taken at right angles to the view shown in Fig. 3 and showing the jaws open, and Fig. 5 is a top view having parts thereof 35 broken off.

Similar characters of reference designate like parts in all the figures of the drawings.

Heretofore, when it has been desired to secure a screw-eye, screw-hook, or analogous 40 fixture in a ceiling—for instance, in the ceiling of a store—for the purpose of suspending various articles therefrom, it has been necessary to use a ladder or similar structure in order to be able to secure such fixtures in place, 45 and which is inconvenient and laborious, not only in the direct use of the same, but also in placing such ladder or structure in position for use and in the removing of the same, especially when the ceiling or other structure 50 is a very high one, and the use of which is, moreover, also dangerous to life and limb. In order, therefore, to overcome these seri-

ous disadvantages, I have provided a means whereby a screw-eye, screw-hook, or analogous fixture can be secured into a ceiling or other high structure by a person standing on the floor and without the use of a ladder or other similar device, and in the preferred form thereof herein shown and described the screw-hook-driving device comprises in a general way a suitable holder (designated generally by A) having secured thereto a pole or handle B and clamping-jaws (designated in a general way by C) movable within said holder for receiving and firmly holding a screw-eye, screw-hook, or analogous fixture in position to be secured in place.

According to one embodiment of my invention the holder A is preferably in the nature of a tubular sleeve 10, having an interiorly-tapered upper end for the reception of a pair of reciprocatory clamping-jaws 11 and 12, and which jaws are secured in said sleeve by means of a bolt or pin 13, extending through and working in oppositely-disposed slots 14 in the sides of the holder and extending through a substantially circular opening 15, formed by a semicircular recess 16, in each jaw. The bolt or pin 13 is provided with a suitable handle or handles 17, extending outside of the holder, and one of which is preferably integral with the bolt or pin and the other of which has a screw-threaded stud 18 fitting within said bolt or pin, and which bolt or pin may be made tubular or have a recess therein for this purpose, said stud 18 engaging with interior screw-threads thereof, whereby said bolt can be secured in position.

Each of the jaws is provided, adjacent to its outer end, with a lip 19 for engaging the shank of a screw-hook or screw-eye, as 50, and with a recess 20 below said lip, and each jaw is also provided at the inner end of said recess with a projecting portion, forming a seat or support 21 for the screw eye or hook 55, whereby said screw eye or hook will be held in position in a manner hereinafter set forth. Each of the jaws has a tapering shank 22 at the inner end in position to be engaged by a pin or stud 23, preferably a screw-threaded pin or stud, extending through a threaded aperture in the tubular holder, whereby on the outward movement of said jaws, by means of the handles 17, the outer faces of said ta-

pering shanks 22 will be engaged by the pins 23 and forced inwardly to thereby open and spread the jaws for the reception of a screw hook or eye, said jaws closing on the hook 5 by the tapering wall of the holder engaging the tapering jaws on their inward movements and pressing the same together in a manner that will be obvious without further description.

10 Secured to the lower end of the holder by any desired means is a suitable pole or handle B, by means of which the device can be held in position for use. The handle or pole may be of any desired length and may be removable therefrom, if desired, and it is herein 15 shown having a portion thereof extending within the tubular holder and secured therein by means of a fastening-pin 26.

As a means for removing the screw hooks 20 or eyes from their position in the ceiling or other place the upper end of each jaw is provided with a slot or recess 28, of suitable length to receive the hook or eye portion or head of the fixture. In the construction 25 shown, however, each jaw has a slot or recess which varies in length from the slot or recess of its companion jaw, whereby different sizes of fixtures can be removed. It will be understood, however, that the screw-driving device is adapted for use with fixtures or devices other than screw-hooks or screw-eyes, if desired; either with or without changing the mouth of the clamping-jaws, without departing from the scope of my invention.

30 In the use of this improved device the clamping-jaws 11 and 12 are moved outwardly in the sleeve or holder by means of the handles 17, whereby the pins or studs 23 engage the shanks 22 of said jaws and open or spread 35 the same. The screw eye or hook 50 is then placed in the mouth thereof, with its hook portion resting on the seat or support 21. The handle 17 is then released, and the jaws by their weight fall within their tapering holder 40 and clamp the screw eye or hook 50 in position between the lips 19, and thus firmly holding the fixture so that it can be screwed into the ceiling or other place by simply turning the handle and without the use of a ladder or 45 other similar device. After the screw-hook or screw-eye has been screwed into its place 50 the holder is drawn away from the same by means of the handle, the hook thereby causing the jaws to move outwardly and spread, 55 whereby the holder can be removed from the hook.

When it is necessary to remove a screw hook or eye for any purpose, the device is placed in position to have one or the other of the slots 60 28 receive the hook, and the handle is then turned to unscrew the same in a manner that will be obvious without a more explicit description.

Having thus described my invention, I 65 claim—

1. In a device of the class specified, the combination of an interiorly-tapered tubular

holder, a pair of tapering clamping-jaws movable therein; each of said jaws having a tapering shank; studs or pins in position in said 70 holder for engaging the tapering shanks of the jaws for opening or spreading said jaws; and a pole or handle secured to said holder.

2. In a device of the class specified, the combination of a holder having a pair of oppositely-disposed slots therein; clamping-jaws movable within said holder; means extending through said slots, and intermediate of and engaging the inner opposing faces of said jaws 75 for moving the same outwardly, whereby the same can be opened or spread; and a pole or handle secured to said holder.

3. In a device of the class specified, the combination of a tubular holder having a pair of oppositely-disposed slots therein; a pair of 85 clamping-jaws movable within said holder, each of said jaws having a semicircular recess in its opposing face; a bolt or pin extending through said slots of the holder and through the substantially circular opening formed by 90 the semicircular recesses of the jaws, whereby said clamping-jaws can be moved outwardly to open or spread the same; and a pole or handle secured to said holder.

4. In a device of the class specified, the combination of a tubular holder having a pair of oppositely-disposed slots therein; a pair of clamping-jaws movable within said holder, each of said jaws having a semicircular recess in its opposing face; a removable bolt or pin 100 extending through the slots of said holder and through the substantially circular opening formed by the semicircular recesses of the jaws and having a handle detachable therefrom, and whereby said clamping-jaws can 105 be moved outwardly to open or spread the same; and a pole or handle secured to said holder.

5. In a device of the class specified, the combination of a tubular holder having a pair of oppositely-disposed slots; a pair of clamping-jaws movable in said holder, each of said jaws having a shank; means extending through said slots and intermediate of and engaging said jaws for moving the same outwardly; 110 means for engaging said shanks to thereby open or spread said jaws; and a pole or handle secured in said holder.

6. In a device of the class specified, the combination of an interiorly-tapered tubular 120 sleeve having a pair of oppositely-disposed slots; a pair of tapering clamping-jaws movable within said sleeve, each of said jaws having a semicircular recess in its opposing face, and also having a tapering shank; a bolt or 125 pin extending through the slots of the sleeve and through the substantially circular opening formed by the semicircular recesses of the jaws; said bolt or pin having a detachable handle, whereby said jaws can be moved outwardly within the holder; studs or pins secured in said holder with their inner ends in 130 position to engage the tapering shanks of said jaws, whereby on the outward movement of

said jaws, they will be spread or opened; and a handle or pole secured to said tubular sleeve.

7. In a device of the class specified, the combination of an interiorly-tapered tubular sleeve having a pair of oppositely-disposed slots; a pair of tapering clamping-jaws movable in said sleeve, each of said jaws having a lip at its upper end, a semicircular recess remotely disposed therefrom, and a recess intermediate of said semicircular recess and said lip, and forming a mouth for the reception of a screw-hook or analogous fixture; each of said jaws also having a tapering shank at its lower end; a bolt or pin extending through the slots of the sleeve and through the substantially circular opening formed by the semicircular recesses of the jaws and having a detachable handle, whereby said jaws can be moved outwardly within the sleeve; studs or pins secured in said sleeve with their inner ends in position to engage the tapering shanks of said jaws, whereby on the outward movements of said jaws, they will be spread or opened; and a handle or pole secured to said tubular sleeve.

8. In a device of the class specified, the combination of a holder, clamping-jaws movable therein; one of said jaws having a recess or slot in its outer end; and a pole or handle secured to said holder.

9. In a device of the class specified, the combination of a holder, clamping-jaws movable therein, each of said jaws having a recess or slot in its outer end, and of a different length from its companion recess or slot; and a pole or handle secured to said holder.

10. In a device of the class specified, the com-

bination of a holder, clamping-jaws movable therein, each of said jaws having a slot or recess in its outer end; and means for opening or spreading said jaws.

11. In a device of the class specified, the combination of a tubular holder having a pair of oppositely-disposed slots; a pair of clamping-jaws movable in said holder, each of said jaws having a recess or slot in its outer end and a shank at the inner end; means extending through said slots and intermediate of and engaging said jaws for moving the same outwardly; and means for engaging said shanks, to thereby open or spread said jaws.

12. In a device of the class specified, the combination of an interiorly-tapered tubular sleeve having a pair of oppositely-disposed slots; a pair of tapering clamping-jaws movable in said sleeve, and having slots or recesses at their outer ends of varying lengths; each of said jaws having a semicircular recess in its opposing face, and also having a tapering shank; a bolt or pin extending through the slots of the sleeve and through the substantially circular opening formed by the semicircular recesses of the jaws, and whereby said jaws can be moved outwardly within the sleeve; studs or pins secured in said sleeve with their inner ends in position to engage the tapering shanks of said jaws, whereby on the outward movement of said jaws, they will be spread or opened; and a handle or pole secured to said tubular sleeve.
